UNITED STATES PATENT OFFICE.

JOHN SAIA, OF BALTIMORE, MARYLAND.

LOCKING DEVICE FOR AUTOMOBILES.

Application filed September 6, 1922. Serial No. 586,442.

To all whom it may concern:

Be it known that I, JOHN SAIA, a citizen of Italy, residing at 126 N. Fremont Ave., in the city of Baltimore and State of Maryland, 5 have invented certain new and useful Improvements in Locking Devices for Automobiles, of which the following is a specification.

This invention relates to locking devices 10 for automobiles, and especially to an improved device for locking the pedals or foot-levers of Ford automobiles.

One object of the invention is to provide a device of this character that any person of ordinary mechanical ability can apply to the ordinary Ford pedals without changing the latter further than boring a few holes through the pedal levers or arms.

Another object is to provide a device of 20 this character that is very difficult and tedious to remove from the pedal-arms when properly applied, so that any one trying to remove the locking device would be liable to attract attention of those who would interfere.

A further object is to provide a device of this character that adds strength to the pedal-arms.

A further object is to provide a device of 30 this character that is adjustable for compensating for wear of the parts operated by the pedals, also adjustable for causing the transmission mechanism to either lock the power-wheels very tightly or less tightly, according 35 to whether or not the automobile may or may not be required to be moved while locked, or according to the operator's judgement in view of different parking laws.

Another object is to provide a device of 40 this character in which each pedal-arm cooperates with the locking device for locking each of the other pedal-arms independently of extraneous objects connected to the locking device.

Another object is to provide a device of 45 this character that has four different locking positions without removing or changing any part of the device; for all its rod-receiving holes are of the proper shape and in the 50 proper relation for permitting the different locking positions to be attained at will of the operator. Therefore, the device can be locked at any desired position (as in Fig. 4) for conforming to different parking regulations and laws, and for making any required 55 or desired adjustment in ordinary use.

Another object in a device of this character, which has four different locking positions, is to arrange its parts for being easily operated without special preparation or 60 practice by the operator; for the operator does not have to practice for becoming familiar with the art or with this device for making the changes. The different positions are felt by the operator's foot at a moment's 65 notice, just the same as the operator feels the difference in changing from "low" to "high" or to "neutral," or in "reversing," etc.; for instance, putting the clutch in "neutral" and applying the brakes to stop at a certain 70 spot, those positions are felt by the touch of the foot. The same principles of the latter are used for locking this device at any desired position—just the same as operating the Ford automobile. 75

Other objects and advantages will be pointed out or implied in the following details of description, in connection with the accompanying drawings in which:—

Fig. 1 is a right side elevation of the Ford 80 pedal-arms having permanently attached parts of the locking device secured thereon, a part of the Ford gear-casing being shown in which the pedal-arms are pivotally mounted.

Fig. 2 is a view of the structure shown in 85 Fig. 1, but the pedal-arms being in the locked position by the addition and insertion of the locking rod and a padlock engaged with the rod.

Fig. 3 is a view of the pedal-arms and 90 locking device as seen from the upper rear or in the direction of the arrow in Fig. 2.

Fig. 4 is a diagrammatic view showing the device in four different locking positions.

Fig. 5 is an enlarged sectional view of 95 the permanently attachable member which fits the left-hand pedal-arm.

Fig. 6 is a sectional view along the line 6—6 of Fig. 5.

Fig. 7 is a side view of the locking rod. 100

Referring to these drawings in detail, in which similar reference characters refer to similar parts throughout the several views, and in which the pedal-arms and their connection with the gear-case are shown for making clear the use and operation of the locking attachment: The invention consists in the construction, application and arrangement or combination of parts as will now be fully described in the following: 105

In the ordinary construction of Ford automobiles, the gear-casing A is apertured at 110

B to provide bearings for the shafts or pivots C on which are secured the respective pedal-arms D, E and F which control the clutch and the reversing and braking mechanisms, respectively. The upper ends of the pedal-arms unite with the middle parts of the pedal-plates G, and the latter have projecting lateral edges that expose their concave surfaces at right angles to the lateral sides of the pedal-arms.

For attachment to the pedal-arms substantially where the latter unite with the pedal-plates, I provide three locking members 10, 11 and 12 each having a groove or channel 13 which fits over the pedal-arm for which it is designed, as the upper ends of the pedal-arms differ in curvature. The flanges or walls of the channels are provided with rivet-holes 14 which serve as guides or templets for use in drilling rivet-holes through the pedal-arms, and these rivet-holes of the locking members are counter-sunk for receiving the heads of rivets 15 and prevent these heads from being cut off with a cold chisel. The bottoms of the channels 13 are curved to conform to the fronts of the pedal-arms (that is, the side next to the front of the automobile), as shown by broken lines in the upper part of Fig. 1, and the upper rear edges of the channel-walls conform to the front surfaces of the contiguous pedal-plates, respectively. When these attachments are held in proper position and then released, they fall into their respective places on the pedal-arms where they may be secured by the rivets and become permanent attachments.

Each of these permanently attached members is provided with a thickened apertured portion 16 and 16^a through which a rod or headed bolt 17 is insertable for locking all the pedal-arms in a substantially fixed relation to one another and to the transmission gear-case, in view of these pedal-arms being secured on spaced and axially parallel shafts or pivots. The rod 17 is apertured at 18 near the opposite end of the rod from its head. A pad-lock 19 of any appropriate kind may have its shackle inserted through the aperture 18, and when it is locked, the rod can not be removed from the members 10, 11 and 12, and so locks them and the pedals against operation.

As the clutch-pedal normally stands in its "high" position, somewhat rearward of the other pedals, its attaching member 16^a is longer than the apertured parts 16, the aperture 16^a being further from the channel-bottom than the rod-receiving apertures of the parts 16 of the members 11 and 12; and to permit vertical adjustments of this arm 16^a, I preferably provide the same with a hinge or pivot-joint 20 whose pivot 20^a has its ends headed, and these heads fit

in the counter-sunk parts provided therefor in the channel-wall to prevent them from being chiseled off.

By providing two rod-receiving holes 21 in each of the members 11 and 12 the rod 17 can be inserted through either one of the holes of either member, so as to lock the power-wheels more or less tightly, and to compensate for wear of the locking or braking mechanism and the reversing mechanism. Moreover, according to circumstances, dependent partly on parking regulations of different States and cities, the owner or user of the automobile may lock the pedal-arms in either of the four combinations or locking arrangements shown in Fig. 4; for instance, by placing the rod 17 in the front apertures of the parts 16, the transmission gearing is permitted to be moved (for changing parking) but offers sufficient resistance to impede the travel of the machine. By placing the rod 17 in the front aperture of the middle device and the rear aperture of the right-hand device, the automobile can be moved a short distance with comparative ease. For ordinary locking, the rod 17 is placed in the rear hole of each of the members 11 and 12. For locking so tightly that the automobile can not be cranked, the rod 17 is placed in the rear hole of the member 11 and the front hole of the member 12.

By providing the thickened portions 16 and 16^a, I not only provide long bearing surfaces for the rod 17, for preventing the rod 17 from being swung in any plane of its axis; but I also add strength of these parts for preventing them from being broken by a would-be thief in attempting to kick the levers free from the lock. Such attempt would also be baffled by the fact that the locking device engages the pedal-arms at their upper ends, so there is no leverage obtained to assist the would-be thief in the attempt to break the lock. The channel-walls and bottom also greatly reinforce and strengthen the pedal-arms.

The holes 21 are made somewhat oblong to compensate for inaccuracies which might result from wear of the transmission mechanism, also from different relative positions of the pedal-arms.

When the device is locked in either the first or last arrangement or relation shown in Fig. 4, the danger of injury to the locked automobile is reduced by the fact that if another automobile shoves it, its transmission mechanism will yield to the pressure or shock, not being "frozen tight."

It will be seen that a locking device of this character can be made and attached at a comparatively slight cost and that it effects a frictional locking of the automobile by positively locking its controlling pedals, so that the automobile can be moved slowly

for re-parking, without injury to any of its parts; but it can not be operated by its own engine's power while thus locked.

It is not intended to limit this invention to the exact construction here shown, but changes may be made within the scope of the inventive idea as described and claimed.

What I claim as my invention is:

1. The locking device which includes members permanently and rigidly united with pedal-arms of an automobile and each being provided with bolt-receiving apertures, each of the apertures of each of said members being movable into alinement with each aperture of another of these members, and a bolt seatable in the alined apertures, for securing these members in different relative positions, means being provided to lock the bolt against removal from the alined apertures.

2. The locking device which includes members each provided with a channel to receive a pedal-arm of an automobile, each of these members being apertured through

said channel to receive rivets for securing it to the pedal-arm, each of these members also being apertured to receive a locking element, a locking element seatable in these bolt-receiving apertures, and locking means to secure the locking element against removal from the volt-receiving apertures.

3. The locking device which includes three channelled members, the channels of these members being respectively shaped to conform to and receive the upper rear parts of the pedal-arms of a Ford automobile, the channel-walls being apertured to receive rivets for securing these members to the pedal-arms, each of these members being provided with bolt-receiving apertures therethrough at right angles to the channels, a bolt seatable in the said apertures, and locking means to secure said bolt against being removed from said apertures.

In testimony whereof I affix my signature.

JOHN SAIA.
